UNITED STATES PATENT OFFICE

170,864

VERTICAL MILLING MACHINE OR SIMILAR ARTICLE

Ingvar O. Johansson, Chicago, Ill.

Application August 28, 1952, Serial No. 21,224

Term of patent 14 years

(Cl. D54—14)

To all whom it may concern:

Be it known that I, Ingvar O. Johansson, a citizen of the United States of America, residing in Chicago, State of Illinois, have invented a new, original, and ornamental Design for a Vertical Milling Machine or Similar Article, of which the following is a specification, reference being had to the accompanying drawing, forming a part hereof.

Fig. 1 is a perspective view of a vertical milling machine, showing my new design.

Fig. 2 is a rear elevation partly in perspective and on an enlarged scale, of the machine shown in Fig. 1.

The essential features of my design reside in the portions shown in full lines.

I claim:

The ornamental design for a vertical milling machine or similar article, substantially as shown and described.

INGVAR O. JOHANSSON.
